(57) **CLAIM**

The ornamental design for a holder, as shown and described.

DESCRIPTION

FIG. 1 is a perspective view of a holder;

FIG. 2 is a front view of the embodiment of FIG. 1;

FIG. 3 is a back view of the embodiment of FIG. 1;

FIG. 4 is a top view of the embodiment of FIG. 1;

FIG. 5 is a bottom view of the embodiment of FIG. 1;

FIG. 6 is a left side view of the embodiment of FIG. 1; and, FIG. 7 is a right side view of the embodiment of FIG. 1.

The broken line showing of the labels, drain holes, mounting holes and feet are for environmental purposes only and form no part of the claimed design.
